Primary Examiner — Shannon W Morgan*Assistant Examiner* — Terilyn Nicole Davis(74) *Attorney, Agent, or Firm* — Justin Lampel**CLAIM**

The ornamental design for a knife handle, as shown and described.

DESCRIPTION

FIG. 1 is a front, left, and top perspective view of a knife handle, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings depict environmental subject matter that form no part of the claimed design.
